(57) **CLAIM**

The ornamental design for a fitness weight set, as shown and described.

DESCRIPTION

FIG. 1 is a perspective view of a fitness weight set showing the new design in a first embodiment.

FIG. 2 is a front view thereof.

FIG. 3 is a rear view thereof.

FIG. 4 is a left side view thereof, the right side being a mirror image.

FIG. 5 is a top view thereof.

FIG. 6 is a bottom view thereof.

FIG. 7 is a perspective view of the fitness weight set showing the new design in a second embodiment.

FIG. 8 is a front view thereof.

FIG. 9 is a rear view thereof.

FIG. 10 is a left side view thereof, the right side being a mirror image.

FIG. 11 is a top view thereof.

FIG. 12 is a bottom view thereof.

FIG. 13 is a perspective view of the fitness weight set showing the new design in a third embodiment.

FIG. 14 is a front view thereof.

FIG. 15 is a rear view thereof.

FIG. 16 is a left side view thereof, the right side being a mirror image.

FIG. 17 is a top plan view thereof; and,

FIG. 18 is a bottom plan view thereof.

The broken away symbols in the drawings indicate that the appearance of any portion of the fitness weight set between the break lines forms no part of the claim design.

The broken lines shown in the drawings depict portions of the fitness weight set that form no part of the claimed design.

1 Claim, 9 Drawing Sheets
